MAN'S AND BOY'S OUTER SHIRT

Alfred P. Rowan, St. Louis, Mo., assignor to Elder Manufacturing Company, St. Louis, Mo., a corporation of Missouri

Application November 12, 1934, Serial No. 752,584

4 Claims. (Cl. 2—115)

This invention relates to a certain new and useful improvement in men's and boys' outer shirts.

The employment of clasps or holders for retaining the necktie-ends closely and flatwise upon the shirt is today quite the vogue. So far as I am aware, such clasps or holders are generally of metallic structure, are separable and detachable from the shirt, are frequently with difficulty and inconvenience attached in tie-retaining position on the tie and shirt, and are often accidentally lost or misplaced, to the resulting loss or inconvenience of the owner.

My present invention has for its object the provision upon, and as substantially an integral or non-separable part of, the shirt of an attractive, inexpensive holder in the form of a flexible loop readily, easily, and with convenience engaged with the necktie-ends for retaining the same efficiently in place approximately flatwise over the shirt-front.

And with the above and other objects in view, my invention resides in the novel features of form, construction, arrangement, and combination of parts presently described and pointed out in the claims.

In the accompanying drawing,—

Figure 1 is a fragmental elevational view of a man's or boy's outer shirt equipped with a necktie-holder of my invention, the front flap of the shirt being shown turned back to display the permanent connection between the shirt and holder;

Figure 2 is also a fragmental plan view of the shirt, illustrating the necktie-holder in concealed position, as when not in use;

Figure 3 is a view similar to Figure 2, showing the necktie-holder presented for use forwardly through the adjacent flap button-hole; and

Figure 4 shows the shirt of Figure 1 and an associate necktie with its ends engaged and retained by the holder.

Referring now more in detail and by reference characters to the drawing, which illustrates a preferred embodiment of my invention, A designates a man's or boy's outer shirt of standard structure, the same as is usual, being open in front and comprising a front portion *a* having a button-equipped marginal portion or flap *1* and a companion front portion *b* having a button-hole equipped marginal portion or flap *2* arranged to overlap the flap *1* for facilitating engagement of the buttons *3* with the holes *4*.

In the present instance, the shirt A is equipped with an attached collar *5*, and arranged upon the shirt A and in engagement with the collar *5*, is

a standard four-in-hand or other necktie B, whose ends *6* depend from the collar *5* over the front or bosom of the shirt A.

C designates a suitable section of preferably silk or other fabricated flexible cord, braid, or the like, which is doubled upon itself into the formation of a loop, and whose ends are, by stitching or other suitable fastening means, permanently secured and fixed, as at *7*, to and upon the inner or under face of the outer or upper shirt-flap *2* adjacent a button-hole, as, in the present instance, the button-hole *4a*.

Accordingly, when not in use or to be used, or abnormally, as it may be said, the loop C will simply depend from, and be concealed from view by, the shirt-flap *2*, as illustrated in Figure 2. However, the loop C is ready at hand for use whenever desired and for use is with facility threaded forwardly through the button-hole *4a*, and the buttons *1* and holes *2* engaged, as is customary, when the shirt A is on the wearer. The loop C is then, or normally, as it may similarly be said, presented forwardly of the shirt A, as shown in Figure 3, and is then with ease and convenience engaged with the depending necktie-ends *6*, the loop C then most efficiently, as a holder, retaining such necktie-ends *6* neatly and attractively in flatwise position over the shirt-front, as illustrated in Figure 4.

The holder C is in itself inexpensive and also with little expense is united as an integral part of the shirt A. Loss of the holder is eliminated, and the holder in no way interferes with the use or care of the shirt, the holder in every respect fulfilling the object stated and most efficiently performing its intended functions.

Having thus described my invention, what I claim and desire to secure by Letters Patent is,—

1. With a shirt with which a necktie will be worn, a section of cord-like material doubled upon itself and having its ends affixed to the front of a shirt in proximate position to present a bight-like loop available on the outer front of the shirt to receive and encircle the end of a necktie.

2. In combination with an outer shirt with which a necktie will be worn, a section of cord-like material doubled upon itself to form a bight-like loop and having its ends stitched to the front of the shirt in closely adjacent position to present a projecting loop to receive and encircle the depending end of a necktie.

3. With a shirt having a front closure provided with button and buttonhole strips, a loop secured on the inside of the buttonhole strip adjacent to a buttonhole and having a bight portion to be pulled

optionally through the buttonhole to present a necktie receiving loop on the outer side and yet allow free buttoning and unbuttoning of the button.

- 5 4. With a shirt provided with a closure strip on its forward side adjacent to which a necktie worn

with the shirt will depend, a cord-like member doubled upon itself to form a bight and having its two ends secured at one side of the strip to present a forwardly projecting loop to receive and hold the depending end of a necktie.

5
